UNITED STATES PATENT OFFICE.

JAMES A. BOOTH, OF WHITBAY, WEST VIRGINIA.

EMERGENCY-SWITCH.

1,341,354.

Specification of Letters Patent.

Patented May 25, 1920.

Application filed October 18, 1919. Serial No. 331,530.

To all whom it may concern:

Be it known that I, JAMES A. BOOTH, a citizen of the United States, residing at Whitbay, in the county of Raleigh and State of West Virginia, have invented certain new and useful Improvements in Emergency-Switches, of which the following is a specification.

This invention relates to an emergency switch or cross-over, and has for its object the provision of means by which a railway car may be diverted from the main track of a railway system on to a spur without cutting the rails of the main track, or the use of switch tongues or frogs, and is particularly adapted to use in mines where it becomes necessary to shift the spurs leading from the main track into lateral tunnels where the face of the material being mined is constantly shifting in a direction parallel to the main track, by the removal from the mine of the material being mined.

I accomplish this object by providing a pair of over-lying rails which are curved to the proper radius, and are so constructed as to present no obstacle in the line of travel of the wheels of a car, and which are superimposed upon the rails of the main track.

For a more comprehensive understanding of my invention, reference may be had to the accompanying drawings, which form a part of this specification and in which:

Figure 1 is a top plan view of the device.

Fig. 2 is a perspective view of the same, showing the means for securing the emergency switch rails to the rails of the main track.

Fig. 3 is a side elevation showing the downward taper of the superimposed rails.

Fig. 4 is a cross section view taken on line *a a* Fig. 1.

Fig. 5 is a cross section view taken on line *b b* Fig. 1.

Fig. 6 is a perspective view of the bridle or spacing member for holding superimposed rails in proper relation to each other.

Fig. 7 is the inner section of a clamp for securing the rails together.

Fig. 8 is the outer section of a clamp for the same purpose.

Like reference numerals refer to like parts throughout the drawings.

1 and 2 are the rails of the main track of a railway system. 3 and 4 are the rails of

the emergency switch, which are superimposed upon rails 1 and 2, and which are tapered downwardly at their inner ends as shown at 5—5, and are straight and lie parallel to rails 1 and 2 for a portion of their length from their inner ends, when they begin to turn outwardly as at 6—6, and which are held rigidly affixed to rails 1 and 2 by clamps 7, 8, 9, and 10, which lie against the inner and outer faces of rails 1 and 2 and 3 and 4, respectively, rails 3 and 4 being held in proper spaced relation to each other by bridle or spacing member 11, which is bent upwardly adjacent its outer ends as at 12—12, in order to provide a clearance over the top of rail 2, and which has bolted thereto wedging chucks or blocks 13, which are adapted to lie against the inner faces of the webs 14 of superimposed rails 3 and 4, and hold the lower outer edges 15 of said rails firmly in the hooked ends 16—16 of bridle or spacing member 11. 17 and 18 are the inner and outer members, respectively, of a clamp between which the main rails and superimposed rails are clamped by means of bolts which are screw threaded at their outer end for the reception thereon of nuts, clamping members 17 and 18 having apertures 19 therethrough adjacent their upper ends, and rails 3 and 4 having apertures therethrough which register with apertures 19 of clamping members 17 and 18, through which bolts are passed, and the nuts screwed up to the desired tension, while apertures 20 are provided adjacent the bottoms of clamping members 17 and 18, and which are adapted to register with each other, and through which bolts, screw threaded at their outer ends for the reception thereon of nuts, are inserted, and the nuts screwed up until the main and superimposed rails are held in a firm grip. Superimposed rails 3 and 4 are recessed on their inner faces for the reception therein of the inner members of clamps 7, 8, 9, and 10, in order that the outer faces of the clamping members will be flush with the inner faces of the superimposed rails. Superimposed rails 3 and 4 lie in the same vertical plane as rails 1 and 2 from their inner ends to the full length of their downwardly tapered portion, in order to provide sufficient clearance for the flanges of the car wheels to pass over the top of rail 2.

Having thus described my invention, what I claim is:

1. The combination with the rails of a railway track, rails superimposed thereon, 5 clamping plates conforming to the contour of the faces of said rails, one of said plates passing under the base of the lower rail and forming a junction with the other of said plates, and means for forcing said 10 plates toward each other.
2. The combination with the rails of a railway track, rails superimposed thereon with a portion of their length lying parallel to the first-named rails and the remainder of their length lying tangentially thereto and removably affixed to the said first-named rails, a spacing element adapted to engage the base of one of the superimposed rails at each end thereof. 15
3. The combination with the rails of a railway track, rails superimposed thereon, with a portion of their length lying tangentially to the said first-named rails, a spacing element adapted to hold locked therein the 20 base of one of the superimposed rails at either end thereof, and a clearance provided in said spacing element for one of the first-named rails.
4. The combination with the rails of a

railway track, rails superimposed thereon, 30 with a portion of their length lying parallel to the first-named rails, and the remainder thereof lying tangentially thereto, a spacing element, flanges carried by the ends of said spacing element and adapted 35 to engage the outer edges of the bases of the last-named rails, and means for locking said rails in engagement therewith.

5. The combination with the rails of a railway track, rails superimposed thereon, 40 with a portion of their length lying parallel to the first-named rails, and the remainder thereof lying tangentially thereto, a spacing member with practically U shaped seats formed in the ends thereof and adapted to 45 receive the bases of the last-named rails therein, and means for locking said bases therein.

6. The combination with the rails of a railway track, of rails superimposed there- 50 on, clamping plates lying against the sides of said rails, said superimposed rails having recesses in the heads thereof for the reception therein of said plates, and means for drawing said plates toward each other. 55

In testimony whereof I affix my signature.

JAMES A. BOOTH.
